UNITED STATES PATENT OFFICE.

SAMUEL R. SARGENT, OF CLEVELAND, OHIO.

DESIGN FOR A WASH-BOARD.

SPECIFICATION forming part of Design No. 20,770, dated May 19, 1891.

Application filed January 14, 1891. Serial No. 377,769. Term of patent 14 years.

To all whom it may concern:

Be it known that I, SAMUEL R. SARGENT, a citizen of the United States, residing at Cleveland, in the county of Cuyahoga and State of Ohio, have invented and produced a new and original Design for Wash-Boards, of which the following is a specification, reference being had to the accompanying drawings, in which—

Figure 1 is a plain elevation of a wash-board which embodies my design, and Fig. 2 is a central longitudinal section of said board.

The leading feature of the design is the corrugated rubbing-surface, a cylindrical portion beneath the same, and the rounded corners of the frame.

A represents the frame of the wash-board, entirely plain upon its surface and having rounded corners *a* at the top.

B is the surface of the rubbing-board, corrugated laterally in curved lines, the said corrugated surface being within the contour of the sides of the frame.

C is a roller in the form of a straight tube or cylinder, and arranged substantially on a plane with the corrugated surface B, and adjacent thereto at its lower portion.

Having thus described my new design, what I claim is—

The design for a wash-board, substantially as shown and described.

SAMUEL R. SARGENT.
